CLAIM

The ornamental design for a security whistle with alarm, as shown and described.

DESCRIPTION

FIG. 1 is a front perspective view of a security whistle with alarm showing our new design;

FIG. 2 is a back perspective view thereof;

FIG. 3 is a front view thereof;

FIG. 4 is a back view thereof;

FIG. 5 is a partially enlarged view of a portion encircled by line 5 in FIG. 4;

FIG. 6 is a right side view thereof;

FIG. 7 is a left side view thereof;

FIG. 8 is a top view thereof; and,

FIG. 9 is a bottom view thereof.

In the drawings, the broken lines represent unclaimed subject matter and form no part of the claimed design.

1 Claim, 9 Drawing Sheets
